CIRCUIT INTERRUPTER

Herbert C. Graves, Jr., East Bradford Township,
Chester County, Pa., assignor to I-T-E Circuit
Breaker Company, Philadelphia, Pa., a corpo-
ration of New Jersey

Application June 6, 1936, Serial No. 83,857

22 Claims. (Cl. 200—87)

My invention relates to electric circuit interrupters or automatic circuit breakers, more particularly to new and improved separable contacts therefor, and has for an object the provision of simple, rugged, and inexpensive contact structures of high current-carrying capacity.

In carrying out my invention, in one form thereof, I provide a rigid self-aligning bridging member having one portion continuously biased into abutting engagement with a stationary contact structure and another portion movable into and out of engagement with another contact structure. The bridging member is provided with a limited freedom of motion about two axes to insure line contact between it and said structures. Intermediate the contact structures, pressure is applied, through a fulcrum and at a single point, to the bridging element to equalize the current flowing to and from opposite ends thereof, and to provide the desired circuit-closing pressures without interfering with the freedom of motion of the bridging member.

Further in accordance with my invention, the bridging member is particularly useful where the stationary contact structures have contact surfaces of considerable length disposed in a plane, or otherwise, as contrasted with relatively narrow or spherical contact surfaces, since the bridging member is readily movable to a position to insure line contact between its plane contact surface and the surfaces of the respective contact structures, to insure maximum current carrying capacity for the circuit interrupter. In the closed circuit position the bridging member is rigidly locked in a fixed position.

Preferably one contact structure includes a plurality of resiliently mounted contact elements whose contact pressures, upon displacement thereof, are substantial. Contact structures of this type are shown and described in my copending application Serial No. 60,017, filed January 21, 1936, for Electric circuit interrupter, now Letters Patent No. 2,090,754, dated August 24, 1937.

Further in accordance with my invention the bridging member is provided with a rounded end biased at all times into abutting contact engagement with one of the contact structures. Preferably the bias is increased as the bridging member is moved into abutting contact engagement with another of the stationary contact structures. A flexible conductor, connected in parallel with the continuously engaged surfaces, is connected to the bridging member above the fulcrum so that upon flow of large currents, a substantial force is applied to increase the circuit closing pressure upon the aforesaid contact surface. The flexible conductor is relatively light, as it is not called upon to carry or withstand the entire current carried by the bridging member.

For a more complete understanding of my in-

vention, reference may be had to the accompanying drawings in which:

Figure 1 is a vertical side elevation, partly in section, of a circuit breaker embodying my invention;

Fig. 2 is a front elevation of the bridging member of Fig. 1;

Fig. 3 is a cross-sectional view of the bridging member and bracket taken along the line 3—3 of Fig. 1;

Fig. 4 diagrammatically illustrates, on a reduced scale, a toggle mechanism of a type suitable to operate and lock the bridging member in a closed circuit position.

Referring to the drawings, I have shown my invention in one form as applied to a circuit interrupter comprising a base or panel member 10 from which is supported a terminal stud or connector 11 connected to a stationary contact assembly or structure 12. A second terminal stud 20 or connector 13, also supported from the panel 10, is connected to a rigid stationary contact structure 14 having a rounded contact surface 15 preferably curved like the surface of a cylinder.

Cooperating with the stationary contact structures 12 and 14 to complete a circuit between them, is a movable rigid bridging member 16, preferably formed of high electrical conductivity material such as copper or an alloy thereof and having a channel-shaped cross-section to increase its rigidity and current carrying capacity. The bridging contact member 16 is supported on a pin 17 carried by the upper ends of the flanges 18 and 19 of a channel-shaped arm 35 or bracket 20. The outer ends of the pin 17 pass through elongated openings or slots 21 and 22 in the flanges 18 and 19 of the bridging member. These openings permit relative horizontal movement between the bridging member 16 and the ends of the pin 17 but substantially prevent vertical movement. By reason of the slots 21 and 22, and the pin 17, the bridging member 16 has a limited freedom of motion about two axes and readily aligns its contact face with the cooperating face 15 of structure 14.

Within rectangular openings in the lower ends of the flanges 18 and 19 is disposed a rectangular operating shaft 23, suitable insulation 24 being provided between the shaft 23 and the flanges 18 and 19 of bracket 20. A U-shaped clamping member 25, encircling the insulated shaft 23, has relatively narrow extensions 26, which pass through the web 20a of bracket 20, riveted tightly against the web 20a to secure the bracket 20 and shaft 23 together.

Any suitable mechanism may be used to operate and lock the bridging member 16 in its closed circuit position, such for example as the mechanism disclosed in U. S. Letters Patent Reissue 60

No. 19,753, issued upon my application Serial No. 711,332. Briefly, such a mechanism, Fig. 4, may comprise a lever 27 rigidly secured to the shaft 23. The lever 27 is shown in the closed circuit position of the interrupter, a pair of toggle links 28 and 29 in conjunction with a crank arm 30 serving positively to lock the member 27 against movement under the influence of a powerful opening spring 31 connected between pivot pins 32 and 33.

The lower end of the crank arm 30 is retained in position by a latch 35 releasable by any suitable electro-responsive device such as an overload magnet 36. A spring 37 normally biases the latch 35 to a position to engage the lower end of the arm 30. The respective toggle links 28 and 29 have stop portions 28a and 29a which engage with each other to prevent movement of the knee pivot 38 of the toggle beyond a slightly overset position. The spring 31, however, having its line of action below pivot pin 39 connecting toggle link 29 to the arm 30, biases the crank arm 30 for rotation in a clockwise direction. Upon occurrence of an overload, the armature 25 of overload magnet 36 releases the latch 35 permitting the crank arm 30 to rotate in a clockwise direction to move the lever 27 and shaft 23 to the open circuit position. As this movement occurs, the knee pivot 38 engages an inclined surface 40 and is thereby moved below its dead center position. The spring 31 is then effective to collapse the toggle 28, 29 downwardly, and at the same time the spring 37 returns the crank arm 30 to a position to be engaged by the latch 35. To reclose the circuit breaker an electromagnet 41 is energized to lift its plunger 42. The knee pivot pin 38 then being located at the lower end of an elongated slot 43 of plunger 42, is thereby lifted to straighten the toggle links 28, 29 and finally to move them to the slightly overset position shown in Fig. 4.

Referring to Fig. 1, it will be observed that the stationary contact structure 14, shown as of solid copper, is arranged so that its curved contact surface 15 is substantially in alignment with the shaft 23. The cylindrical surface 15 is of relatively large radius, its axis and the axis of the shaft 23, however, being disposed in a horizontal plane normal to the panel 10. The lower end of the bridging member 18 is provided with a cylindrical, or curved, surface 46, the radius of which extends from the axis of the shaft 23, though it may extend from an axis disposed slightly above that of shaft 24 and slightly nearer the bridging member 18. The plane contact surface of the bridging member 18 is of course tangent to the curved surface 46. In any event the surface 46 is formed so that it is not moved or forced, during the opening of the circuit interrupter, by the contact structure 14 toward the axis of the shaft 23.

By means of a spring 47 clamped by a steel plate 48 against the web of the bridging member 18, the lower or curved end of the bridging member is at all times maintained in contact engagement with the structure 14. The spring 47 need not be heavy or particularly strong inasmuch as only a relatively light pressure is necessary to insure substantial conductance between surfaces 15 and 46.

In accordance with the present invention the continuous engagement of the surfaces 15 and 46 permits the use of a flexible conductor 49 of greatly reduced size. One end of the conductor 49 is secured to the contact structure 14 by a cap screw

50, the conductor being looped around the shaft 23 and the bracket 20, with its opposite end secured by cap screw 51 to a lug or projection 52 integrally secured to the web of the bridging member 16 and extending outwardly between the flanges 18 and 19 of the bracket 20.

The flexible conductor or shunt 49, connected in parallel with the contact surfaces 15 and 46, is not called upon to carry currents of large magnitude during normal operation of the circuit interrupter. It is preferably included, however, in order substantially entirely to eliminate arcing between the surfaces 15 and 46. Since it is of light weight, as contrasted with the heavy flexible conductors heretofore used, it is not subject to failure due to repeated operations, as it is highly flexible; moreover, it does not interfere in any way with the opening and closing operations of the circuit breaker.

Application of circuit closing pressure to the bridging member 16 is provided by means of a pressure applying member or button 54, disposed below the projection 52 and carried by the web 20a of the arm or bracket 20. As best shown in Fig. 3, the member 54 comprises an enlarged head 25 having a hardened steel surface 54a which is a part of the surface of a sphere. An integral threaded extension 54b extends through an opening in the web 20a and is clamped into position by means of a nut 55. A plurality of relatively thin washers 56 are placed between the head of the member 54 and the outer face of the web to provide for adjustment of the member with respect to the web 20a. Cooperating with the hardened steel surface 54a is the steel plate 48 which, by rivets 58, is secured to the web of the bridging member 16, and, as mentioned above, is clamped against the spring 47.

The upper contact structure 12 is preferably of a type similar to that shown in my aforesaid Patent No. 2,090,754. More particularly, a plurality of relatively narrow rigid bridging elements 61, each of which has a rounded end pivoted in a recess 62, are respectively supported by means of spring supports 63 and associated springs 64. The spring supports 63 at their upper ends rest upon re-entrant portions of a contact block 65 forming a part of the structure 12. Their opposite and lower ends rest in recesses formed in side plates of the contact structure 12, only one of which, the side plate 66, is shown. In the closed circuit position, shown in Fig. 1, it will be observed that each of the bridging elements 61 has been rotated in a clockwise direction against the bias of its associated spring 64. If desired, a plurality of rigid bridging elements 61 may be assembled in groups within the same recess, each element of each group being supported by its own spring. For greater current carrying capacity a plurality of elements and a plurality of recesses may be provided in a single contact structure, or, two or more structures may be electrically connected in parallel to form one current path of a circuit, the remaining current paths, if desired, each including additional structures electrically connected in parallel with each other.

To relieve the foregoing contact structures 12 and 14 of the duty of making and breaking the circuit, there is provided in the upper part of the contact structure 12 an arcing contact 71 carried by an arm 72, itself journaled on a pivot pin 73 supported between the aforesaid side plates of the structure 12. A biasing spring 74 connected to one end of the arm 72 and to a

stationary pin 15 is effective to maintain the lower end of the arcing contact 11 in a position first to be engaged by the bridging member 16 during its closing movement. The arcing contact 11, by means of a relatively heavy flexible conductor 76, is connected to the contact block 65 of structure 12. In this instance a heavy conductor may be safely used without danger of failure due to fatigue, or repeated operations, since the pivotal movement of the arcing contact 11 is relatively small. In consequence, the conductor 76 is not placed under excessive stress; it neither impedes nor interferes with movement of the arcing contact 11. Outward movement of the arcing contact may be limited by engagement of the lower end 77 of the arm 12 with the pin 15. The lower part of the arcing contact 11 and a cooperating part of the bridging member 16 are respectively provided with inserts 78 and 79 formed of arc-resistant conductive material, such as, for example, a material containing tungsten.

It will now be assumed that the bridging member 16 is in its open circuit position and that the electromagnet 41 has been energized to close the circuit interrupter. As its associated core 42 straightens the toggle 28, 29, the arm 27 rotates the shaft 23 in a counterclockwise direction, as viewed in Figs. 1 and 4, to move the arm or bracket 20 and the bridging member 16 toward the closed circuit position.

At all times, and during the aforesaid movement, the surfaces 15 and 46 are maintained in contact engagement. During the closing movement the relative radii of surfaces 15 and 46 are preferably such that the contact pressure increases, or, the lower end 46 of the bridging member 16 is moved, against the bias of spring 41, toward shaft 23. Since both surfaces 15 and 46 are cylindrical, or are generated respectively by parallel lines moving in predetermined curved paths, they at all times engage one another along a line as contrasted with a point. Line contact is assured since the bridging element 16 is free to move, because of the openings 21 and 22, an amount sufficient to take care of any inherent inaccuracies incident to manufacture or assembly of the parts. Moreover, closing movement of the bridging member 16 by the arm or bracket 20 is relatively independent of the pin 17 since the pressure applying member or button 54 is utilized to apply the circuit closing pressure to the bridging member 16. During closure of the interrupter the pin 17 serves merely as a support for the bridging member and prevents vertical movement thereof.

Continuing with the circuit-closing operation, as the upper end of the bridging member 16 approaches its closed circuit position, its arc-resistant insert 79 is moved into engagement with the insert 78 of the arcing contact 11 to form a current path through the interrupter. Substantially all of the current flows from one of terminals 11 and 13 to the other terminal, by way of the bridging member 16; only a small fraction of the current flows by way of the flexible conductor 49.

As the closing movement continues, the arcing contact 11 is rotated about its pivot 73 and against the bias of the spring 14. The opposition offered by the spring 14 not only increases the contact pressure between inserts 78 and 79 but also effects a further increase in the contact pressure between surfaces 15 and 46. This is desirable since contact conductivity increases

with increased pressure. The reason for the increased pressure will be clear by considering the bridging member 16 as a lever pivoted for movement over the fulcrum or pressure applying member 54. The force acting outwardly on the upper end of the bridging member 16 produces an opposite force on the lower end of the bridging member 16 effective to press surface 46 against surface 15.

Upon further movement of the bridging member 16 the lowermost one of bridging elements 61 is first engaged by the bridging member 16. Additional movement of the bridging member 16 forces that bridging element downwardly against the bias of its associated spring. In the same manner the remaining bridging elements 61 are successively engaged by the bridging member 16 and each of them is forced downwardly against the bias of its associated spring, the associated contact surfaces engaging and wiping each other clean to insure minimum resistivity.

By deflection of the elements 61 against the bias of their springs, the contact pressure between contact surfaces 15 and 46 is further increased. As before, the pressure applying member 54 located intermediate the contact structures 12 and 14, serves substantially to produce equal conductivities at the engaging contact surfaces.

In the fully closed position, Figs. 1 and 4, the toggle 28, 29, has been moved slightly beyond its dead center position and the pressures upon the contact surfaces are sufficient to insure a maximum current carrying capacity.

In case additional contact pressures are desired, or in the event of wear of the engaging surfaces, additional laminations or washers may be interposed between the enlarged end or head of the pressure applying member 54 and the web 20a. The additional laminations, by varying the position of member 54, adjust the position of the bridging member 16 with respect to the arm or bracket 20 and cause a greater movement of the arcing contact 11 and of the respective bridging elements 61 against the bias of their associated springs. On the contrary, if the number of laminations are decreased, the contact pressures, or the extent of movement of the bridging member 16 to its fully closed position, are decreased.

Upon the occurrence of an overload, particularly overloads of short-circuit magnitude, a substantial amount of current momentarily flows through the flexible conductor 49. At the same time, the increased current flowing from contact structure 14 through the bridging element 16 may produce magnetic forces of a magnitude tending greatly to decrease the contact pressures between surfaces 15 and 46. However, the increased current flowing through the looped conductor 49 likewise produces magnetic forces producing tension in the conductor 49. These forces are applied to the projection or post 52 in a direction to produce a torque on the bridging member 16 which acts in a clockwise direction about the fulcrum or member 54. Therefore the forces produced by current flowing in the conductor 49 act in direct opposition to the forces produced by the current flowing between structure 14 and the bridging member 16. The electromagnetic forces acting on the bridging member above and below the pressure member 54 substantially balance each other so that there is no tendency to reduce pressure at the lower contact. The effect of the upper terminal contacts is to increase the

pressure at both terminals during flow of over-load current.

Heretofore, under short-circuit conditions, bridging members, themselves being resilient, or resiliently mounted as by springs interposed between the operating arms and the bridging member, have been subject to the forces tending to move the bridging member out and away from contact-engagement with associated contact structure. The result was a decrease in the current carrying capacity of the interrupter at the very time a maximum current carrying capacity was desired.

As shown above, however, in accordance with my invention, tendency of the bridging member 16 to move away from the associated contact structure 14 is effectively prevented by the rigid fulcrum or pressure applying member 54, and by the arrangement of the circuit connections so that the magnetic forces produced are ineffective. As more fully explained in my aforesaid co-pending application, the assembly of elements 61 is such that the magnetic forces tend to increase the pressures upon opposite ends thereof. Similarly, any current flowing through flexible conductor 76 produces magnetic forces tending to increase the contact pressure upon the inserts 78 and 79.

It is to be understood the duration of a current of short-circuit magnitude is very short. In fact, as soon as a predetermined current flows, the overload magnet 38 is effective to release the latch 35. Thereupon, and as described above, the crank arm 30 is released and the powerful spring 31 quickly moves the arm 20 and the bridging member 16 to the open circuit position. In this instance the pin 17 is moved into engagement with the right hand walls, or sides, of the elongated openings or slots 21 and 22 to move the bridging member 16 to the open position.

During the opening movement the bridging member 16 successively disengages the bridging elements 61, the current being thereby transferred to the conductor 76 and the arcing contact 71. The circuit is opened as soon as the inserts 78 and 79 are separated. If an arc forms between the inserts 78 and 79, current continues to flow. Since the contact pressure between surfaces 15 and 46 has been decreased by the movement of bridging member 16 to its open-circuit position, it is highly desirable, to prevent arcing between surfaces 15 and 46, to provide the shunt or flexible conductor 48 in all cases where the circuit interrupter is called upon to open circuits carrying current of short-circuit magnitude.

Circuit interrupters of the type shown are usually provided with arc extinguishing means effective to extinguish quickly the arc. Consequently even though a substantial amount of current may flow through the conductor 48, the duration of its flow is so short that the conductor 48 is in no way damaged.

While I have shown a particular embodiment of my invention it will be understood that I do not limit myself thereto, since many modifications may be made, and I, therefore, contemplate by the appended claims to cover any such modifications as fall within the spirit and scope of my invention.

What I claim is:

1. In a circuit breaker having spaced contact structures one of which is resilient, a bracket rotatable about a fixed axis located adjacent one of said structures, a rigid bridging member sup-

ported by said bracket with one end portion thereof adjacent both said axis and said one of said contact structures, operating means rigidly connected to said bracket for rotating said bracket and said bridging member from an open circuit position to a closed circuit position, and means operable during all circuit-opening and circuit-closing movement of said bridging member for biasing said end portion of said bridging member into abutting engagement with said one of said contact structures, said operating means including a rigid pressure-applying member disposed in abutting engagement with an intermediate portion of said bridging member for displacing said bridging member and said resilient contact structure to produce between both of said contact structures and said bridging member circuit-closing contact pressures.

2. A circuit interrupter having spaced contact structures, an actuating member, a rigid bridging member loosely connected to said actuating member for limited freedom of motion about two axes, a rigid pressure transmitting member supported by one of said members and engaging the other of said members at a single point lying between said contact structures, and means for applying a circuit-closing pressure to said actuating member, said bridging member pivoting about said pressure-applying member to insure line contacts between one face thereof and said contact structures.

3. In a circuit interrupter, spaced contact structures, a self-aligning bridging member for completing a circuit between said contact structures, operating means therefor including a connection providing limited freedom of motion of said member relative to said operating means, means biasing one end of said bridging member into abutting engagement with one of said structures during all opening and closing movement of said member, and means for applying circuit-closing pressure to said bridging member without interfering with its freedom of motion to insure minimum contact resistance between said bridging member and said contact structures.

4. In a circuit interrupter, a rigid bridging member, associated spaced contact structures, means, including a bracket pivotally supporting said bridging member, for applying pressure to said member intermediate its opposite ends, resilient means, without the path of current through said member and said structures, operable by said pressure for development of circuit-closing contact pressures between said member and both of said structures, means for operating said bracket to produce movement of said bridging member into and out of abutting engagement with at least one of said spaced contact structures and for locking said member in circuit-closing position, and means for adjusting the position of said bridging member with respect to said operating means to control the magnitude of said circuit-closing pressures.

5. In a circuit interrupter, spaced contact structures, a solid bridging member formed of high conductivity material provided with a plane contact surface for engaging said structures and with integral flanges extending away from said surface, a steel plate carried by said member intermediate said flanges, a supporting bracket loosely pivoted to said flanges adjacent one end of said bridging member, a pressure-applying member carried by said bracket for abutting engagement with said plate at a region intermediate said spaced contact structures, actuating

- means connected to said bracket for applying, through said pressure-applying member and said plate, circuit-closing pressure to said bridging member.
5. 6. In a circuit interrupter, a rigid bridging member, associated contact structures, a bracket pivotally supporting said bridging member at one end thereof, a rotatable operating member connected to the opposite end of said bracket for rotating said bracket to move said bridging member into and out of abutting engagement with said associated contact structures, and a member carried by said bracket and adjustable to change the angular position of said bridging member with respect to said bracket.
10. 7. In a circuit interrupter, spaced contact structures, at least one of which is resilient, a bridging member movable into and out of abutting engagement with at least one of said structures, a bracket pivotally connected to said bridging member, an adjustable member for changing the angular position of said bridging member with respect to said bracket, means for rotating said bracket to move said member into and out of contact-engagement with one of said contact structures, and a spring effective at all times to bias said member into engagement with another of said structures.
15. 8. In a circuit interrupter having spaced contact structures at least one of which is resilient, an operating member extending in front of said structures, a bridging member loosely connected to said operating member for movement into abutting engagement with said structures, co-operating members supported respectively by said bridging member and said operating member for applying a circuit closing pressure to said bridging member intermediate said contact structures, and a spring interposed between said members for biasing them away from each other, and a flexible conductor connected to said bridging member and to one of said structures.
20. 9. In an electrical circuit interrupter, cooperating spaced contact structures, one of which includes a plurality of diagonally disposed rigid bridging elements, and associated leaf springs for opposing movement of said bridging elements, and the other of which includes a rigid contact face; a bridging member having a limited freedom of motion about two axes, an actuating member for moving said bridging member into and out of abutting contact engagement with at least one of said structures, a fulcrum disposed intermediate the ends of said bridging member and between said structures, a shaft supporting said actuating member and said bridging member for rotation about an axis adjacent one of said structures, and biasing means at all times maintaining contact engagement between said bridging member and said last-named contact structure.
25. 10. In a circuit interrupter, a rigid channel-shaped bridging member formed of copper and having flanges to impart rigidity thereto, a channel-shaped bracket disposed between said flanges and pivotally connected at one end thereof to said member, and an operating member secured to the opposite end of said bracket.
30. 11. In a circuit interrupter, a bridging member formed of copper and provided with flanges to impart rigidity thereto, a channel-shaped bracket disposed between said flanges and pivotally connected to said member, an operating member secured to said bracket for rotating said bracket to move said bridging member between predetermined positions, stationary contact structure en-
- gaged by said bridging member during its said movement, a spring supported between said bracket and said bridging member for biasing at all times one portion of said bridging member into engagement with said contact structure, and another stationary contact structure engageable and disengageable by said bridging member.
35. 12. In a circuit interrupter, a bridging member formed of copper and provided with flanges to impart rigidity thereto, a bracket disposed between said flanges and pivotally connected at one end thereof to a corresponding end of said member and means for rotating said bracket to move a plane contact surface of said member into and out of a circuit-closing position, the opposite end of said bridging member curving toward said rotating means with a radius of curvature substantially equal to the distance between the pivotal axis of said bracket-rotating means and said plane contact surface.
40. 13. In a circuit interrupter, movable contact structure comprising a channel-shaped bridging member having one end rounded away from an adjoining plane contact surface, flanges integral with said member, an operating member, a channel-shaped bracket nesting between said flanges of said bridging member, means securing said bracket to said operating member, a terminal member secured to said bridging member and extending between said flanges and outwardly to one side of said bracket, resilient means interposed between said bracket and said bridging member for producing a bias tending to separate said bracket and said bridging member, stationary contact structure associated with said bridging member, and a flexible conductor connected to said structure and to said terminal member.
45. 14. In a circuit interrupter, a movable contact structure comprising a rigid bridging member having opposite ends rounded away from a connecting plane contact surface, flanges integral with said member, an operating member, a bracket having flange portions disposed between the flanges of said bridging member, pivot means interconnecting corresponding upper portions of said bracket and said bridging member, means securing the lower portion of said bracket to said operating member, and resilient means supported by, and interposed between, said bracket and said bridging member for exerting a bias tending to separate the lower portions of said bracket and of said bridging member, and stationary contact structures one of which is disposed adjacent the lower portion of said bridging member, and another of which is disposed adjacent the upper portion thereof, each of said stationary contact structures presenting contact surfaces for abutting engagement by said bridging member.
50. 15. In a circuit interrupter having spaced contact structures one of which is displaceable against an associated biasing means, a rigid bridging member one portion of which is continuously in abutting contact-engagement with one of said structures, an operating member for moving another portion of said bridging member into and out of abutting contact-engagement with the other of said structures, and means for producing predetermined contact-pressures upon said abutting surfaces comprising a pressure-applying member for controlling the extent of displacement of said one of said structures against the bias of its associated biasing means.
55. 16. In a circuit interrupter having spaced contact structures one of which is rigid and another of which is displaceable against an opposing
60. 65. 70. 75.

- biasing means, a rigid bridging element, one surface of which is continuously in abutting engagement with a surface of one of said structures, an operating member movable from one position to another position, means loosely connecting said bridging member to said operating member to insure line contact between said abutting surfaces, said operating member being effective to move another contact face of said bridging member into and out of abutting engagement with a contact face of another of said structures, and means for controlling the displacement of the resiliently biased structure comprising a member intermediate said contact structures, and between said operating member and said bridging member, and engaging one of them at a single point about which said bridging member has a limited freedom of motion.
17. In a circuit interrupter having spaced contact structures one of which is rigid and another of which is displaceable against an opposing biasing means, a rigid bridging element, one surface of which is continuously in abutting engagement with a surface of one of said structures, an operating member movable from one position to another position, means loosely connecting said bridging member to said operating member to insure line contact between said abutting surfaces, said operating member being effective to move another contact face of said bridging member into and out of abutting engagement with a contact face of another of said structures, means for controlling the displacement of said biased structure comprising a member intermediate said contact structures and between said operating member and said bridging member and engaging one of them at a single point about which said bridging member has a limited freedom of motion, and a spring for maintaining contact pressure between said continuously engaged surfaces.
18. In a circuit interrupter having spaced contact structures one of which is rigid and another of which is displaceable against an opposing biasing means, a rigid bridging element, one surface of which is continuously in abutting engagement with a surface of one of said structures, an operating member movable from one position to another position, means loosely connecting said bridging member to said operating member to insure line contact between said abutting surfaces, said operating member being effective to move another contact face of said bridging member into and out of abutting engagement with a contact face of another of said structures, means for controlling the displacement of said biased structure comprising a pressure-applying member intermediate said contact structures and between said operating member and said bridging member and engaging one of them at a single point about which said bridging member has a limited freedom of motion, a flexible conductor connected in parallel with said continuously engaged surfaces, and a spring for maintaining contact pressure between said continuously engaged surfaces.
19. In a circuit interrupter having spaced contact structures, a bridging member disposed for abutting contact engagement with said structures to complete a circuit therebetween, a flexible conductor one end of which is connected to one of said structures, means connecting the

opposite end of said conductor to said bridging member, said conductor forming a loop around one end of said bridging member, an operating member for rigidly holding said bridging member against said contact structures, and a rigid fulcrum carried by one, and engaging the other, of said members at a point intermediate the ends of said loop. 5

20. In a circuit interrupter having spaced contact structures one of which is displaceable against an opposing biasing means, a bridging member disposed for abutting contact engagement with said structures to complete a circuit therebetween, the path of current between one of said contact structures and said bridging member producing a magnetic force tending to separate them, a fulcrum locked in a fixed position against said bridging member, and a flexible conductor secured to said bridging member and forming a current path to produce a magnetic force on the side of said fulcrum remote from said one contact structure and in a direction to oppose said first-mentioned magnetic force. 10 15 20

21. A circuit interrupter comprising spaced contact structures formed of rigid members, a rigid bridging member in circuit-closing position disposed in abutting contact engagement with said members, the path of current between each structure and said bridging member producing a force tending to separate them, resilient means spaced from the regions of said abutting contact engagement for producing circuit-closing contact pressures between said bridging member and said structures, releasable operating means for rigidly locking said bridging member in circuit-closing position, and rigid means actuated directly by said operating means and engaging said bridging member intermediate its ends to form a fulcrum about which said magnetic forces oppose each other, and for equalizing said contact 30 35 40 pressures.

22. A circuit interrupter comprising spaced contact structures, a rigid bridging member, biased to a circuit-opening position, having spaced non-resilient contact surfaces for abutting contact engagement with non-resilient contact surfaces of said structures to complete a circuit for current flow between them, the paths of the current entering and leaving said member respectively producing magnetic forces tending to separate said abutting surfaces, resilient means adjacent one end of said bridging member, without said paths of current, for developing circuit-closing contact pressures between all of said abutting surfaces, means for operating said bridging member to open and close said circuit and including releasable means locked in circuit-closing position and engaging said bridging member intermediate its ends rigidly to restrain it in circuit-closing position and to maintain said resilient means under stress for said development of said contact pressures, said engaging means while locked in said circuit-closing position forming a fulcrum about which said magnetic forces oppose each other, and means for releasing said locking means to produce movement of said bridging member to said circuit-opening position, said magnetic forces then assisting in the acceleration of said bridging member to said circuit-opening position. 45 50 55 60 65 70
